UNITED STATES PATENT OFFICE.

HARVEY H. ENTZ, OF LEESBURG, FLORIDA.

TROUSERS.

1,359,973.

Specification of Letters Patent. Patented Nov. 23, 1920.

Application filed June 17, 1918. Serial No. 240,466.

To all whom it may concern:

Be it known that I, HARVEY H. ENTZ, a citizen of the United States, residing at Leesburg, in the county of Lake and State of Florida, have invented certain new and useful Improvements in Trousers, of which the following is a specification.

The invention has for its principal object to preserve creases in garments intended 10 to maintain a fold or crease.

In its specific application the invention is intended for trousers so as to preserve the crease lines in the front and in the rear of the leg members.

15 In accordance with the present invention the material is woven in a manner so that the portion intended to present the creases or fold is made thicker than the remaining portion, the purpose being to preserve the crease line, and also to withstand the strain to which the crease line portion is subjected.

20 It is a matter of common knowledge that trousers bag at the knees after a comparatively short period of service. This is due chiefly to the strain on the fabric when the latter is stretched when the leg is bent, when 25 in a sitting posture. To give the trousers a neat and tidy appearance it is necessary 30 to have the same tailored or pressed at frequent intervals.

35 The present invention relates chiefly to the method whereby the fabric during the process of weaving is thickened along the crease line, whereby the same is enabled to withstand strain and thereby prevent bagging at the knee and at the same time preserving the crease line and obviating the necessity for frequent pressing.

40 The drawing illustrates a preferred embodiment of the invention, however, it is to be understood that in adapting the same to meet different conditions, various changes in the form, proportion, and minor details 45 of construction may be resorted to without departing from the nature of the invention as claimed hereinafter.

In the drawing:

50 Figure 1 is a front view of a pair of trousers embodying the invention,

Fig. 2 is a sectional view of a portion of fabric woven in accordance with this invention,

Fig. 3 is a transverse section of a trousers leg on the line 3—3 of Fig. 1, showing the 55 parts on a larger scale.

Corresponding and like parts are referred to in the following description and indicated in the several views of the drawing by like reference characters.

Inasmuch as the invention is peculiarly adapted for trousers it is shown applied in this connection, and in Fig. 1 the letter A designates a pair of trousers of ordinary construction but provided with crease portions embodying the invention. The trousers are constructed of material embodying the invention and a portion of such material is indicated in Fig. 2 in which 1 represents the material and 2 a thickened portion, which corresponds with the crease line 3 of the trousers.

During the weaving of the fabric 1 a narrow portion thereof is made considerably thicker as indicated at 2 and this thickened portion coincides with the crease or fold of the trousers or other garment formed from the fabric. It is to be understood that the fabric is woven with especial reference to its particular use so that unusual waste 75 will be prevented in the forming of the garment from the fabric. As is well known the leg members of trousers are provided with front and rear creases as indicated at 80 3 in Fig. 3. The present invention contemplates having the leg members of the trousers thickened along the crease lines 3 so as to maintain the crease lines and preserve 85 a neat and tidy appearance to the garment.

Trousers have the front portions subjected to unusual strain when in service, this being due to the stretching of the fabric over the knee when the leg is bent. By thickening the crease line portion the trousers leg is reinforced so as to withstand the 95 strain, and as a result the crease line is maintained.

The foregoing description and the drawings have reference to what may be considered the preferred, or approved, form of 100 my invention. It is to be understood that I may make such changes in construction and arrangement and combination of parts, materials, dimensions, et cetera, as may prove expedient and fall within the scope of the 105 appended claims.

Having thus fully described my invention, what I claim as new and desire to secure by Letters Patent is:—

1. A garment having its fold or crease line reinforced and maintained by having the fabric woven thicker along a line coinciding with the said fold or crease.

2. As a new article of manufacture, trousers having the crease lines of the leg members woven thicker than the remaining portion of the fabric. 10

In testimony whereof I affix my signature.

HARVEY H. ENTZ.
